HANDLE FOR TANK TYPE SUCTION
CLEANERS OR THE LIKECharles H. Sparklin, Chicago, Ill., assignor to
Birtman Electric Company, a corporation of
Illinois

Application September 24, 1945, Serial No. 618,175

1 Claim. (Cl. 16—115)

1

This invention relates to a tank type suction cleaner or the like, and particularly to an improved handle for such a cleaner.

Tank type cleaners are adapted to rest on the floor during the cleaning operation, and to be dragged around from place to place by means of the nozzle hose. As these cleaners are of compact shape it is necessary that a handle be provided so that they can be easily carried from room to room. The handles that have been proposed heretofore project above the surface of the cleaner casing and break the symmetrical effect of the casing. I have invented a handle that blends into the cleaner casing when the handle is at rest, but which can be easily grasped and raised above the surface of the casing, so that the cleaner can be moved from place to place. This new handle is of very simple construction, and adds very little to the total weight of the cleaner. It has a pleasing appearance and when not in use is depressed so as to be out of the way.

The invention will be described as shown in the embodiment as set out in the accompanying drawings. Of the drawings, Fig. 1 is a side elevation of a tank type suction cleaner including the improved handle; Fig. 2 is a plan view of the cleaner with portions broken away for clarity of illustration; and Fig. 3 is an enlarged sectional elevation taken substantially along line 3—3 of Fig. 2 and showing the handle in side elevation.

The tank type cleaner comprises a horizontal elongated casing 10 supported above the floor by means of wheels 11 and a rest 12. Near the front of the casing is located an inlet opening 13, to which the nozzle tubing is to be attached. At the rear of the casing is located an outlet opening 14 to which a blower attachment may be affixed. On top of the cleaner there is placed a starter button 15, and the improved handle 16.

The handle 16 is preferably located above the center of gravity of the cleaner, and extends longitudinally to the casing. The handle comprises a substantially horizontal portion 17, adapted to be grasped by the hand, and horizontal ears 18 extending from each end of the handle's horizontal portion 17. These ears 18 extend into cavities 19 that are also horizontal, and are formed in separate portions 20 of the cleaner casing. These cavities are larger in cross-sectional area than the corresponding area of the ears. The handle is so arranged that the ears are raised to the top of the cavities when the handle is lifted, but sink within the cavities when the handle is released. The cavity-forming portions of the casing 20 extend above the main body

portion of the casing so that the top of the handle and the top of the cavity-forming portions are substantially in one plane when the handle is at rest. The handle extends between the cavity-forming portions, and all lie longitudinally to the body of the cleaner.

In order to facilitate grasping of the handle at the top of the casing there are provided depressed portions 21 in the casing at either side of the handle, so that the handle may be readily grasped when it is at rest. The portion of the handle to be grasped is also made relatively thin. When the cleaner is lifted the handle is pulled away from the main body portion 10 of the cleaner until the ears 18 engage the top of the cavities (Fig. 3). The cleaner can then be carried to a new location. As soon as the handle is released it sinks down into the casing (Fig. 1) and the top of the handle is flush with the top of the casing as shown in Fig. 1 and by dotted lines in Fig. 3.

As shown in the drawings, the handle assembly for the tank type cleaner that includes the elongated casing 10 comprises a mounting structure attached to the top of the vacuum tank or casing 10 to provide an elongated ridge of substantially uniform width and height. This ridge, which includes a pair of hollow end members 20 and a central extensible handle member 17 positioned therebetween, is of substantially uniform width and height. The end members 20, as shown in the drawings, each have substantially vertical side walls 20a and a top wall 20b, with these walls of the respective end members terminating in respective spaced vertical planes to form U-shaped abutment surfaces 20c on each end of the member to define vertical openings in the respective end members 20 and facing each other. The handle member 17 fits snugly between these abutment surfaces 20c on the end members 20 and includes a central handgrip 17a, as shown in Fig. 1 and end portions 17b extending downwardly from the handgrip 17a to support the handgrip in spaced relation to the vacuum tank 10. These end portions have plane vertical end surfaces disposed substantially perpendicularly to the handgrip, with each of these end surfaces being adjacent to and engaging a corresponding abutment surface 20c of one of the end members 20. Each end portion has adjacent the bottom thereof a horizontal rigid ear 18 parallel to and directed away from each end of the handgrip 17a. Each ear 18 extends into the opening in the adjacent end member 20 with each of these ears being of a vertical thickness considerably less than the height of the opening into which it extends so as

to permit limited vertical movement of the handle member when the vacuum cleaner is lifted. The bottom surface of each downwardly extending end portion 17b rests on the top of the vacuum tank or casing 10 when the handle is in its retracted position, as shown in Figs. 1 and 2. The rigid ears engage the bottom surfaces of the top walls 20b of the respective end members 20 when the handle member is extended, as shown in Fig. 3. As is shown in Fig. 2, the structure on either side of the handgrip 17a is depressed as indicated at 21 in order to facilitate gripping of the handgrip 17a.

Having described my invention in detail, it is my intention that the invention be not limited to these details of description, but rather be construed broadly within its spirit and scope, as set out in the accompanying claim.

I claim:

A handle assembly for a tank type vacuum cleaner having an elongated casing, said handle assembly comprising a mounting structure attached to the top of the vacuum tank and providing an elongated ridge of substantially uniform width and height, said ridge extending longitudinally of the elongated casing and including a pair of spaced hollow end members and a central extensible handle member positioned therebetween, said end members each having vertical side walls and a top wall, the walls of the respective end members terminating in respective spaced vertical planes to form an inverted U-shaped abutment surface on each end member, said abutment surfaces defining vertical openings in the respective end members with said openings facing each other, said handle member fitting snugly between said abutment surfaces and having a central handgrip and end portions extending downwardly from said handgrip to support the handgrip in spaced relation to the

vacuum tank, said end portions having plane vertical end surfaces disposed perpendicularly to the handgrip, each of said end surfaces being adjacent to and engaging a corresponding abutment surface of one of said end members, each end portion having adjacent the bottom thereof a horizontal rigid ear parallel to and directed away from each end of the handgrip, each ear extending into the opening in the adjacent end member, each of said ears being of a vertical thickness considerably less than the height of the opening into which it extends so as to permit limited vertical movement of the handle member when the vacuum cleaner is lifted, the bottom surface of each downwardly extending end portion resting on the top of the vacuum tank when the handle is in its retracted position and the rigid ears engaging the bottom surfaces of the top walls of the respective end members when the handle member is extended, said structure on either side of said handgrip being depressed in order to facilitate grasping of the handgrip.
